Primary Examiner — Vy N Koenig*Assistant Examiner* — Qiawen W Wiechert(74) *Attorney, Agent, or Firm* — Jose Cherson Weissbrot(57) **CLAIM**

The ornamental design for a food trolley as shown and described.

DESCRIPTION

FIG. 1 is a top front left perspective view of a food trolley showing my new design;

FIG. 2 is a bottom back right perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of the food trolley shown in use. The broken lines in the drawings are for the purpose of illustrating portions of the food trolley that form no part of the claimed design.

1 Claim, 9 Drawing Sheets(56)
